(57) **CLAIM**

The ornamental design for a finish sample display, as shown and described.

DESCRIPTION

FIG. 1 is a perspective view of a finish sample display showing our new design;

FIG. 2 is a front elevational view thereof;

FIG. 3 is a top plan view thereof, the bottom being a mirror image of the side shown;

FIG. 4 is a left side view thereof, the right side being a mirror image of the side shown; and,

FIG. 5 is an enlarged side view of a sample.

The broken lines depict unclaimed environmental subject matter.
